UNITED STATES PATENT OFFICE.

LYNEWOOD M. HASTINGS AND RICHARD W. LEUTWILER, OF CHICAGO, ILLINOIS.

STEAM-TRAP.

1,170,150.

Specification of Letters Patent.

Patented Feb. 1, 1916.

Application filed January 12, 1915. Serial No. 1,729.

To all whom it may concern:

Be it known that we, LYNEWOOD M. HASTINGS and RICHARD W. LEUTWILER, citizens of the United States, residing in the city of Chicago, county of Cook, and State of Illinois, have invented certain new and useful Improvements in Steam-Traps, of which the following is a specification.

This invention relates to improvements in steam traps and more particularly to automatically operating valve mechanism for steam traps, heating systems and the like.

The salient objects of the invention are to provide an improved valve mechanism of the character referred to, which will permit the water of condensation to pass into the return pipe but will effectively prevent the passage of steam therein; to provide a construction in which the expansible member for automatically actuating the valve is positioned where the water of condensation must pass over it before discharging into the steam pipe; to so arrange the parts that the force of gravity is employed for pulling the condensation water toward the expansible member rather than away from it; to provide a construction in which the steam trap is divided into upper and lower compartments, the upper of which serves as an expansion chamber and discharges downwardly through a relatively small opening directly on to the valve mechanism; to provide a construction which can be employed with heating systems of the vacuum type without danger of the steam being sucked into the return pipe unless first directly contacting with the diaphragm containing the expansible fluid; and in general to provide a simple and efficient automatically controlled steam trap which can be economically manufactured and conveniently assembled, and in which the various parts are readily accessible in case it is necessary to adjust or repair any part.

The invention further resides in various features of construction and combinations of parts as hereinafter set forth.

In the drawings—Figure 1 is a top plan view of a steam trap embodying our invention, the cover being removed; and Fig. 2 is a vertical cross section through the trap.

Referring in detail to the particular embodiment of our invention illustrated in the drawings, 1 designates the main casing of the steam trap which is provided at its lower end with an outlet nipple 2, adapted to re-

ceive the threaded end of a return pipe 3. Upon the opposite side of the trap and near its upper edge, an inlet 4 is provided. The mouth of this inlet is formed in the shape of a tapered seat 5 against which the inner end 6 of the inlet pipe 7 is seated by means of a lock nut 8. Near its central portion the trap is provided with a tapered seat 9, against which seats the edge portions 10 of a diaphragm 11, and extending upwardly from the diaphragm 11 is a spider 12 which terminates at its central portion in a seat 13. This seat is employed as a bearing portion against which the inner end 14 of a set screw 15 presses, the set screw being adjustably carried by the cover 16 and the construction being such that by tightening down the set screw the edge portions 10 of the diaphragm 11 are forced into a tight seal with the seat 9. At its central portion the diaphragm 11 is provided with a discharge opening 17, the diaphragm being preferably concave so that the water of condensation will drain toward the opening 17.

Just beneath the diaphragm opening 17 is positioned a valve 18 carried by the upper wall 19 of an expansible member 20. The lower wall 21 of this diaphragm has a screw threaded stud 22 which engages a threaded seat 23 in the lower wall of the casing 1. Between the walls 19 and 21 the member 20 is provided with an expansible fluid 24, this fluid being sufficiently sensitive to heat so that the water of condensation normally passing through the opening 17 toward the return pipe 3 will not expand it sufficiently to close the valve 18, but if steam starts to pass through the opening 17, the increased temperature will cause the fluid to expand sufficiently to raise the upper wall of the expansible member 19 and move the valve 18 against its seat 25.

In assembling the trap the expansible member 20 is secured to the casing by screwing threaded stud 22 into the threaded seat 23. The diaphragm 11 is then placed in position with its marginal portions 10 engaging the seat 9, and after screwing the cover 16 onto the casing the diaphragm is locked in position by turning the set screw 15 until its inner end tightly presses against the seat 13. In order to prevent the escape of steam around the set screw we preferably provide a supplemental cap 26 which fits over the upper end of said screw.

In using the trap in heating systems of

the vacuum type the inlet 4 is connected to the discharge from the radiator and the outlet 2 connected to the return pipe. The discharge from the radiator therefore passes 5 first into the portion of the trap above the diaphragm 1, this diaphragm in reality dividing off an upper chamber. From here the water of condensation can only pass into the lower portion of the casing through the 10 outlet 17. As it passes through this opening it strikes the curved surface of the valve 18 and is deflected downwardly onto all portions of the diaphragm, and from the diaphragm drips off on to the lower part of the 15 casing and passes into return pipe. If, however, the steam should not be all condensed in the upper portion of the casing, it will in passing out through the opening 17 be forced to directly contact with the ex- 20 pansible member, and this effectively guards against steam being sucked into the return pipe without actuating the valve governing means. It is obvious from the above description that the expansible member is not 25 only positioned directly in the path of the water of condensation but is so arranged relative to the discharge opening that the force of gravity is utilized for drawing the heated products directly on to the dia- 30 phragm rather than away from it.

While we have shown and described an embodiment of our invention in which the inlet and outlet are both adapted for connection with horizontal pipes, it is obvious that 35 either might be vertical and that various other changes in construction and arrangement of parts can be made without departing from the scope of our invention. Also, while the invention has been described with 40 reference to its use in heating systems of the vacuum type, it is obviously applicable to other uses, and we do not desire to limit our invention except as specified in the appended claims.

45 We claim as our invention:

1. A steam trap comprising a casing having an inlet and an outlet, said casing having a seat formed on its inner face between said inlet and outlet, a diaphragm having an 50 opening therein disposed against the seat to divide the casing into compartments, a thermostatically actuated valve for coöperation with the opening in the diaphragm to control communication between the compartments, and adjustable means carried by the casing to hold the diaphragm tightly engaged against the seat.

2. The combination with a casing having a seat formed centrally therein, said casing 60 being open at its upper end, a diaphragm

engaged against the seat to divide the casing into an upper compartment and a lower compartment, said casing having an inlet communicating with the upper compartment and an outlet communicating with the lower 65 compartment, the diaphragm being formed with a central opening to establish communication between said compartments, a cover to close the upper end of said casing, means carried by the cover to hold the diaphragm 70 tightly engaged against the seat, a valve disposed in the lower compartment to control communication between the compartments of the casing, and an expansible member for automatically actuating said valve upon 75 predetermined change in temperature within the casing.

3. The combination with a casing having an open upper end and a central seat formed therein, a diaphragm having a central opening therein arranged against valve seat to divide the casing into an upper compartment and a lower compartment, a valve arranged within the lower compartment and adapted to coact with the opening in the dia- 80 phragm to control communication between the compartments of the casing, an expansible member for automatically actuating said valve upon predetermined change in temperature, a cover adapted to detachably 85 close the open end of the casing, and adjustable means carried by the cover to tightly hold the diaphragm in engagement against the seat.

4. The combination with a casing having 95 an open end and a central seat formed therein, a diaphragm arranged within said casing and having a central opening therein, said diaphragm dividing the casing into two compartments, a valve arranged in one of 100 said compartments to coact with the opening in said diaphragm for controlling communication between the compartments, an expansible member for automatically actuating said valve upon predetermined change in 105 temperature, a spider formed on said dia- phragm and extending into the other compartment, a cover for closing the open end of the casing, said cover having a centrally threaded opening therein, and a screw 110 mounted in the threaded opening for engagement against the spider whereby to maintain the diaphragm in engagement against the seat.
